UNITED STATES PATENT OFFICE

2,560,236

ELECTRIC OVERHEAD DOOR OPENING
AND CLOSING DEVICE

James N. McNinch and Lawrence E. Myers,
Sterling, Ill., assignors, by direct and mesne
assignments, to Sterling Electronic Door Con-
trol Corporation, Sterling, Ill., a corporation
of Illinois

Application November 15, 1948, Serial No. 60,102

8 Claims. (Cl. 268—59)

1

This invention comprises novel and useful im-
provements in an electric overhead door opening
and closing device and more specifically pertains
to a power operated control device for overhead
doors of garages or the like of the type having
limiting switches for the open and closed posi-
tions of the door for controlling an electric mo-
tor for actuating the door mechanism, and re-
sides generally in an improved control means for
sliding the door in response to actuation of the
electric motor.

The primary object of this invention is to pro-
vide an improved and simple construction of
operating means for imparting the opening and
closing movement to an overhead door construc-
tion.

A further object of the invention is to provide
an operating means having the facility of opera-
tion which characterizes a sprocket chain and
wherein improved housing and guiding means
are provided for retaining the operating means
for reciprocating movement without deviation
from its longitudinal path of reciprocation.

An important feature of the invention resides
in the provision of a channel-shaped operating
track having upper and lower guide surfaces
therein and a medial longitudinal slot in the up-
per wall thereof, through which slot extends the
lower end of the door supporting carriage which
is pivotally connected to one end of the sprocket
chain operating member, this sprocket chain be-
ing slidably received between the upper and lower
guide surfaces to prevent buckling or distortion
of the chain during the push and pull movement
imparted thereto by the power operating mecha-
nism.

Yet another feature of the invention resides in
the construction of the operating track which in-
cludes a horizontal bottom wall, parallel verti-
cally disposed side walls and inwardly extending
top walls overlying the bottom wall and spaced
from each other to provide a longitudinal slot for
guidingly receiving the lower end of the door
supporting carriage, the lower ends of the de-
pending flanges overlying the upper ends of the
rail carried by the bottom wall to guidingly re-
ceive the upper and lower surfaces of the sprock-
et chain connecting pins therebetween.

Yet another feature of the invention resides in
the provision of a construction as set forth in the
preceding features wherein the side links of the
sprocket chain are adapted to overlie the adjac-
ent edges of the bottom guiding rail in the upper
flanges or guiding ribs, to establish a lateral guid-
ing action of the chain therebetween.

2

These, together with further ancillary objects
and features of the invention which will become
later apparent as the following description pro-
ceeds, are attained by this mechanism, a pre-
ferred embodiment of which has been illustrated
by way of example only in the accompanying
drawings, wherein:

Figure 1 is a fragmentary vertical longitudi-
nal sectional view through a portion of a door, a
door frame and supporting construction, and
showing the principles of this invention applied
thereto;

Figure 2 is a vertical transverse sectional detail
view, taken substantially upon the plane of the
section line 2—2 of Figure 1, parts being broken
away, and illustrating the manner of mounting,
guiding and operating a door in accordance with
this invention;

Figure 3 is a diagrammatic view illustrating
the electrical connections for controlling the mo-
tor for operating the door in accordance with the
principles of this invention;

Figure 4 is a fragmentary detail view taken
upon an enlarged scale substantially upon the
plane of the section line 4—4 of Figure 1 and il-
lustrating in particular the manner in which the
door supporting carriage is associated with the
door operating rail and the door operating means;
and

Figure 5 is a further vertical sectional view
taken substantially upon the plane of the broken
section line 5—5 of Figure 4.

Referring now more specifically to the ac-
companying drawings, wherein like numerals
designate similar parts throughout the various
views, attention is directed primarily first to
Figures 1 and 2 wherein the numeral 10 design-
ates a portion of a door framework which is
adapted to be closed by a door consisting of a
plurality of panels 12 hinged together as at 14
to form a flexible type of door although the in-
vention is obviously equally applicable to the
non-sectional type, which will normally be ver-
tically disposed to close the opening in the door
frame 10.

In this type of door, commonly employed for
garages or the like, a track or guideway 16 of
known design and of channel shaped construc-
tion is provided for guidingly and slidingly re-
ceiving guide and support rollers 17, see Figure
2, with which the door panels 12 are provided
to enable the door to be lowered into its vertical
position as shown in Figure 1 for closing the
door, or to be alternatively lifted and reset into

a horizontal position above the door opening for giving access to the door opening.

A pair of parallel horizontally extending tracks 18, preferably in the form of channel members, are mounted in any suitable manner upon the door containing structure, and constitute door carriage tracks for guidingly receiving and supporting a pair of door carriages indicated generally by the numeral 20 and which consist essentially of T-shaped members, having supporting wheels 22 journaled on the ends of the arms of the T and by means of which the carriage and the door carried thereby is supported.

The uppermost panel 12 of the door has rigidly mounted thereon on a supporting bracket 24 which is pivoted intermediate the ends of the leg of the T-shaped carriage 22, a construction which will later become apparent. Thus, as the T-shaped carriage 20 rolls along the door carriage tracks 18, the door panels 12 are slidingly moved in their tracks 16, first vertically and then horizontally, as will be apparent from Figure 1. As the door moves from the horizontal position, the endmost panel pivots about the pivot or fulcrum pin upon the carriage 20 to accommodate the relative changes of motion.

A pair of channel-shaped door operating tracks 26 are likewise carried by the door containing structure and are positioned below the carriage tracks 18. A door operating means, in the form of a sprocket chain construction 28 is slidingly and guidingly mounted in each of the operating tracks 26 and that one end is pivotally connected to the end of the carriage member 20 which extends into and is slidingly guided in the track 26.

The door is mechanically operated as by means of an electric motor 30, which is preferably of the split phase induction type, the shaft 32 of this motor driving a main operating shaft 34 by means of a sprocket gear drive 36. The ends of the main shaft 34 by means of sprocket chain drives 38 drive a pair of jack shafts 40 suitably journaled upon the supporting framework for the door. These jack shafts 40 carry sprocket wheels 42, see Figure 1, which extend into the operating tracks 26 and engage with the sprocket chain operating means 28 adjacent one end thereof for imparting a pushing or a pulling motion selectively to this chain as set forth hereinafter.

Reference is now made more particularly to Figures 4 and 5 for an explanation of the construction of the operating means and the operating track. The track 26 consists of a channel member having a bottom wall 44 with an upstanding longitudinal medial rib 46 thereon which constitutes a lower guide surface, the sides of the bottom wall 44 having parallel vertical upwardly extending side walls 48 whose upper ends are inwardly turned to form top walls 50 which terminate in spaced relation to each other to provide a central longitudinal slot in the top walls through which the depending leg of the T-shaped carriage 22 extends and slides.

The inner extremities of the top walls 50 are downwardly turned as at 52 to form parallel guides along the sides of the above-mentioned slot, the lower edges of these flanges constituting ribs forming upper guide surfaces which overlie and are in a constant spaced relation with respect to the rail 46.

The operating means includes a sprocket chain 28 which is formed of a plurality of articulated elements, each of these elements or segments

consisting of a pair of spaced parallel links 54 which are terminally connected to the ends of adjacent links, by means of connecting pins 56 about which are provided spacer rollers 58. The endmost link of the sprocket chain is pivoted by the end pivot 56 to the lowermost end 58 of the downwardly extending leg member 59 of the T-shaped carriage 22. As will be readily seen from Figure 4, and from Figure 5, the upper and lower surfaces of the sleeves 58 of the pins are slidingly and guidingly received between the adjacent guide surfaces of the depending ribs 52 and the upstanding rail 46 to thus prevent buckling of the sprocket chain links and thus positively constrain and confine the same to a straight line reciprocation. Further, as shown in Figure 4, the links 54 overlap the adjacent guide surfaces of the rail 46 and the ribs 52, to constitute a lateral guiding means which prevents the sprocket chain from being withdrawn laterally from between the guide surfaces. Thus, the sprocket chain is limited to a straight reciprocatory movement between the two guide surfaces, and consequently the carriage 22 is likewise confined to a similar movement. By reason of the engagement of the sprocket wheel 42 therewith, the motor 30 is thus enabled under the control of a directing switch assembly to selectively impart a pushing or pulling motion to the sprocket chains 28, to the carriage 22 and to the door mounted thereon.

As shown in Figures 1, 4 and 5, the supports 24 are pivoted or journaled upon lateral support and pivot pins 60, by means of sleeves or bushings 62 thereon, these pins being welded or otherwise rigidly attached and extending laterally from the legs 59 of the carriage members.

Likewise rigidly carried by the legs 59 of the carriage members 22, are laterally extending lugs 40 or fingers 64 which are adapted to engage limiting switches disposed in their path of travel as set forth hereinafter, for the purpose of stopping the actuation of motor 30 at the two extremes of the door position.

As will be readily seen from Figures 2, 4 and 5, the depending legs 59 of the carriage members 22 are goosenecked or suitably curved in shape to enable the rollers 22 to lie directly above the pivot 60 and the sprocket chain link pins 56.

Any suitable means may be provided for controlling the operation of the motor 30 to operate the mechanism for raising or lowering the door. However, one suitable form of electrical circuit has been diagrammatically illustrated in Figure 3, wherein the electric motor 30 is shown as being of the split base type and is connected to electrical leads 70 and 72 which communicate in any desired manner with any suitable source of electric current, the lead 72 being connected to the terminals of the split base motor 30, while the lead 70 is connected with a reversing switch 74 to thereby control the direction of rotation of the motor 30. Also connected to the motor circuits are limiting switches 76 and 78 of any suitable construction, and which are mounted upon the structure with which the door operating mechanism is associated, in such a manner that the finger 64 on each of the carriage members 22 is enabled to engage and actuate one of the switches 76 and 78 at the extremes of the movement of the door. Thus, when the switch 74 is manually operated, the motor 30 is placed in motion and the door is either open or closed, and as it approaches its extreme position, one of the switches 76 or 78 is operated to open the circuit

and discontinue operation of the motor. When the switch 74 is thrown to the other direction, the operation is reversed, the other one of the switches 76 or 78 against stopping the door when it has reached its extreme position.

Since various known electrical circuits and systems are available for carrying out this operation, the actual electrical system in itself forms no part of the invention and hence is not deemed to be necessary of further illustration.

From the foregoing, the manner of constructing and operating the device will be readily understood and further explanation is believed to be unnecessary. However, since numerous modifications and changes will readily occur to those skilled in the art after a consideration of the foregoing specification and the accompanying drawings, it is not desired to limit the invention to the exact construction shown and described, but all suitable modifications and equivalents 20 may be resorted to falling within the scope of the appended claims.

Having described the invention, what is claimed as new is:

1. In an overhead door control device, a door, tracks for slidably receiving said door, a pair of horizontal door carriage tracks, a door carriage engaged in each track and secured to said door, a door operating track paralleling one of said support tracks, a flexible operating means slidably guided in said operating track for straight line push and pull motion, said door carriage being connected to one end of said operating means, a driving member connected to said operating means for imparting reciprocation thereto and a source of power connected to said driving member, said operating track including a channel member having a bottom, side walls and inwardly extending top walls providing a medial, longitudinal slot therebetween, said carriage extending through and being slidable in said slot, said bottom wall having a longitudinal rail forming said lower guide surface, said top walls having depending, parallel and longitudinal flanges forming said upper guide surfaces.

2. The combination of claim 1, wherein said operating means comprises a sprocket chain, the chain pins of said chain being slidably received between said rail and flanges and extending across said slot.

3. The combination of claim 2, wherein the links of said chain overlap the adjacent edges of said rail and flanges for lateral guiding engagement therewith.

4. An operating track for a flexible member subjected to reciprocatory motion, said flexible member being attached to an operating arm com-

prising; a bottom, parallel and laterally spaced sides attached to said bottom, inwardly extending top walls on said sides, the adjacent edges of the top walls being laterally spaced to define a medial, longitudinal slot therebetween, said arm extending through said slot and being slideable therein, said top walls having depending, parallel and longitudinal flanges forming upper guide surfaces, said bottom having a longitudinal, medial rib forming a lower guide surface, said upper and lower guide surfaces slidably receiving said flexible member in non-buckling position therebetween.

5. The combination of claim 4, wherein said flexible member comprises a sprocket chain, said chain having link pins, said flanges engaging the upper surface of said link pins, said rib engaging the lower side of said link pins.

6. In an overhead door control device, a door, tracks for slidably receiving said door, a pair of horizontal door carriage tracks, a door carriage engaged in each track and secured to said door, a door operating track paralleling said support track, a sprocket chain slidably guided in each operating track for straight line push-pull motion, said operating track having an upper guide surface and a base, a longitudinal medial rail on said base, said sprocket chain being slidably and guidably disposed in non-buckling position between said upper guide surface and said rail.

7. The combination of claim 6, including parallel longitudinal ribs depending from said operating track and forming said upper guide surface, said rail and said ribs engaging the link pins of said sprocket chain on the upper and lower sides thereof.

8. The combination of claim 7, wherein the links of said sprocket chain laterally overlap the adjacent edges of said rail and ribs for lateral guiding engagement therewith.

JAMES N. McNINCH.
LAWRENCE E. MYERS.
